UNITED STATES PATENT OFFICE.

JOHN P. PROST, OF ST. LOUIS, MISSOURI.

IN-A-WALL FURNITURE.

Application filed January 22, 1919. Serial No. 272,760.

To all whom it may concern:

Be it known that I, JOHN P. PROST, a citizen of the United States, residing in the city of St. Louis and State of Missouri, have invented certain new and useful Improvements in In-A-Wall Furniture, of which the following is a specification.

My invention relates to in-a-wall furniture, and more particularly to an article of furniture for use in a kitchen, or other room, in the form of a combined table, chairs and cabinet and when closed having the face thereof appear as a panelled section of the wall. A further object of the invention is to provide the article in such form as being capable for use as a writing desk and filing cabinet. A further object of my invention is to overcome the objections to the use of ordinary furniture such as cabinets and desks in a small room, and this I overcome by the use of my in-a-wall furniture.

With the above objects in view and others as the nature of the invention is better understood, the article consists in the novel construction, combination and arrangement of parts hereinafter fully described and finally pointed out in the claim hereto appended.

Referring to the accompanying drawings forming a part of this specification wherein like characters of reference denote similar parts throughout the several views:

Fig. 1, is a front elevation of an article of in-a-wall furniture in closed position and constructed in accordance with my invention.

Fig. 2, is a front perspective view of the article shown in Figure 1, as it appears when open.

Fig. 3, is a vertical sectional view of the article shown in Figure 1.

Fig. 4, is a sectional view taken on lines A—A of Figure 1, looking in direction of the arrow.

Fig. 5, is a front perspective view of a modified form of my improved in-a-wall furniture in the form of a writing table and filing cabinet.

In carrying out the aim of my invention, I provide a cabinet frame comprising four uprights 1 arranged in pairs suitably spaced apart at each side of the base portion of the cabinet and adapted to form seat compartments therebetween. I also employ a pair of uprights 2 suitably spaced apart, and arranged intermediate the two inner up-

rights 1 adapted to form a table-top compartment therebetween at the lower end thereof, and a shelf compartment therebetween at the upper end thereof, as will be more fully understood hereinafter. The upper end of each two uprights 2 forms the side wall pieces of the upper cabinet section, as clearly shown in Figure 3, of the drawings. A top piece 3 is mounted upon each pair of uprights 1 forming a top closure, as clearly shown in Figure 3. A top piece 4 is fixed to the upper ends of the uprights 2 and form the top of the upper receiving cabinet section. The upper receiving cabinet section is provided with a plurality of shelves 5.

The frame work also includes the facing strips 6, the panel front 7 for each seat compartment, and the panel front 8 for the table-top compartment.

The cabinet frame is also provided with two hinged doors 9 forming closures for the upper part of the upper receiving cabinet section. A hinged door 10 forms a closure for the lower part of the upper cabinet section. Two hinged doors 11, form front closures for the seat compartments arranged in the lower part of the cabinet section near the top thereof, as clearly shown in Figure 1, of the drawings.

The cabinet frame is further provided with the back pieces 12 and 13, as clearly shown in Figure 4.

The cabinet frame proper is arranged or set in the wall between the studdings 14, as clearly shown in Figures 1 and 4 either before or after the plastering has been applied to the balance of the wall.

A table-top 15 is operatively supported in the table-top compartment formed between the two uprights 2, and the lower shelf 5, as clearly shown in Figure 3. The table-top 15 is shown in full lines in its closed position, which is a substantially vertical position. In order to permit of vertical adjustment of the rear end of the table-top 15, I provide the table-top 15 with two trunnions 16 adapted to move up and down in the vertical slot 17 in each upright 2. The upper ends of the slots 17 form a stop for the rear end of the table-top 15 when in an open position, as indicated in dotted lines in Figure 4. In order to add further support for the rear end of the table-top 15, I permit the upper face of the rear edge thereof to come into engagement with the lower edge of the back

piece 12, as shown in dotted lines in Figure 4. The lower face of the table-top 15 near the rear end thereof may rest upon the facing 6 which facing acts as a support, as is manifest. The table-top 15, it will be observed, cannot be opened or extended for use until the door 10 is opened.

A seat 18 is operatively supported in each seat compartment formed between each pair of uprights 1 as clearly shown in Figure 3. Each seat 18 is shown in full lines in this view as in its closed position, which is substantially vertical. In order to permit of vertical adjustment of the rear end of each seat 18, I provide each seat 18 with a pair of trunnions 19 adapted to move up and down in the vertical slot 20 in each upright 1. The upper end of each slot 20 forms a stop for the rear end of the seats 18. In order to provide further support for the rear end of each seat 18, I permit the upper face of the rear edge thereof to come into engagement with the lower edge of the back piece 13, as shown in dotted lines in Figure 4. The lower face of each seat 18 near the rear end thereof is adapted to rest upon the upper edge of the front panel 7, as is manifest, and indicated in dotted lines in Figure 4. It will be observed that the seats 18 cannot be opened or extended for use until after their respective doors 11, are opened, as indicated in dotted lines in Figure 4.

From the foregoing it will be readily understood that when it is desired to use the table-top 15, that it is first necessary to lower or open the door 10 before raising the table-top, into an extended horizontal position, as is manifest.

When it is desired to use the seats 18, it is first necessary to lower or open the doors 11 and then raise the seats 18, finally bringing them to an extended horizontal position, as clearly shown in Figure 2. The seats 18 it will be observed are arranged on opposite sides of the table-top 15 and intermediate the table-top 15 and the floor of the room.

It will thus be seen that when no table or seats are desired exposed in the room, that they may be concealed in the wall from view, and when desired for use may be quickly adjusted to form a table-top and seats, or either, independent of the other.

The modification shown in Figure 5, of the drawings, is exactly like Figures 1, 2, 3 and 4, excepting that the seat compartments and seats are eliminated and that the shelves 5 are provided with upright partitions 21, thereby rendering the shelves useful for filing away papers or the like, and rendering the device useful as a writing desk and filing

cabinet, instead of an article of kitchen furniture.

My improved article of in-a-wall furniture can be built in a kitchen, kitchenette, 65 pantry, breakfast-room or infirmary, and, in fact any place a table; a table and chairs; a table, chairs and cabinet; or writing desk, or writing desk and chair or chairs may be needed, or desired.

From the foregoing description it will be seen that I provide an article of furniture of the in-a-wall type which is most useful and convenient in rooms where floor space is lacking or small, and an article of furniture, the many advantages of which will readily suggest themselves to those skilled 75 in the art to which it appertains.

I am aware that the exact details of construction shown in the drawings are not 80 essential to the invention, and that various minor changes may be made without departing from the spirit of my invention, hence I reserve the right to make any such changes or modifications as may fairly fall within 85 the scope of the appended claim when fairly construed.

What I claim is:

In-a-wall furniture of the class described comprising, in combination, a pair of opposed uprights arranged in spaced relation, 90 a top piece for said uprights, a back piece for said uprights extending from the top piece to a point intermediate the top piece and the bottom edges of said uprights, a front wall for said uprights, a door hinged- 95 ly connected at its lower edge to said front wall to complete a compartment between the uprights back piece and front wall, a board member receivable in a vertical position within said compartment, a trunnion extending laterally from each side face of the board member near the rear end thereof and receivable in opposed slotted openings in the uprights which openings extend from 100 a point near the lower edge of the uprights to a point adjacent the lower edge of the back piece, said board member capable of being raised and extended forwardly in a horizontal position with relation to the uprights when the hinged door is moved to its 110 position, said board member when in its extended position resting both upon the lower face of the hinged door and the upper face of the front wall and the upper face of the 115 board member at its rear edge engaging the lower face of the back piece for guiding and retaining the board member in its horizontally extended position.

In testimony whereof, I have hereunto signed my name to the specification.

JOHN P. PROST.
